UNITED STATES PATENT OFFICE.

MAXIMILIAN JACKER, OF CHICAGO, ILLINOIS.

STEAM-ENGINE VALVE MECHANISM.

SPECIFICATION forming part of Letters Patent No. 465,576, dated December 22, 1891.

Application filed June 22, 1891. Serial No. 397,156. (No model.)

To all whom it may concern:

Be it known that I, MAXIMILIAN JACKER, a citizen of the United States, residing at Chicago, in the county of Cook and State of Illinois, have invented a new and useful Steam-Engine Valve Mechanism, of which the following is a specification.

My invention relates to an improvement in steam-engines, and particularly to an improvement in the operation of the steam-valves.

The matter of primary importance, viewed from an economic standpoint, to be considered in the organization of a steam-engine, whether for one purpose or another, is the problem of utilizing the expansion of the steam in the greatest possible amount in the actual operation of the engine—that is, to avoid waste of steam by throttling so far as possible and to regulate the introduction of steam into the cylinder according to the amount of work intended and its nature. Besides the waste incident to throttling another source of waste arises from the employment of the ordinary link-motion for regulating the speed. The automatic cut-off engine generally in use—namely, the Corliss—employs a wrist-plate with rod, connection with somewhat complicated valve-gear for operating the steam-valve; but there are two important objections to this arrangement. The first is that the valve cuts off at a period much in advance of the limit of throw of the piston—that is, at a point about four-tenths or less than one-half of the throw—and in case of a slight increase of resistance, requiring the steam to follow beyond that point, it naturally refuses to regulate properly, because then it allows the steam to follow until the valve is closed directly by the wrist connection. The second objection is found in the necessary dependence for closing the valves on the action of a spring or vacuum, which, in order to secure promptness of action, involves a certain surplus of power beyond that otherwise required for the same purpose. Besides this, it is well known that the Corliss valve-gear, as generally used, acts automatically only under the normal engine speed.

The object of my invention is, primarily, to provide for the regulation of the expansion during the whole length of the stroke of the

piston; secondly, to provide a means whereby the speed of the engine may be regulated entirely by the cut-off without resorting to the throttle, which is opened wide when starting and closed only for stoppage.

A further object of my invention is to provide a means by which a change in speed may be accomplished without interfering with the action of the governor, which may be adjusted for any speed while running through the operation of a light lever or hand-wheel.

A further object of my invention is in the particulars above outlined and in other particulars which will presently appear, to effect a material improvement in the operation of the engine, principally for the saving of steam, and to simplify in essential particulars the operation of the steam-valve mechanism, whereby the operation of the engine may be more easily and more readily controlled, automatic regulation continuing without regard to the action of the engineer.

With the above objects my invention consists, primarily, in a steam-engine in which the steam-ports are closed alternately by the operation of a steam-cylinder and piston or similar auxiliary agent regulated immediately by the governor, the operation of this auxiliary agent being associated with a direct opening and closing operation from a swinging or revolving wrist driven by the engine-shaft.

My invention consists, furthermore, in an arrangement of steam-valve-operating mechanism, by the employment of which the port at one end of the cylinder may be closed when or before the engine-piston arrives at the other end; but its immediate valve-operating lever is always held firmly at the right place for a positive opening of the port, so that the lead of the valve remains constant.

My invention consists, further, in a steam-engine in which the steam-valve-operating rods, one of which—viz., the immediate valve-operating rod—is actuated by the motion of the drive-shaft and the other of which is actuated by the auxiliary agent, are connected together in such a manner that each in turn acts as a fulcrum for the throw of the valve-lever, thereby affording a differential movement in the valve-lever, the effect of which is to permit the valve to be closed at any time

during the movement of the piston without interfering with the position of the immediate valve-operating rod, which continues to open and close the valve.

5 My invention consists, further, in the general and specific details of construction and combination of parts, all as hereinafter more fully set forth.

In the drawings, Figure 1 is a view in elevation of a steam-cylinder, showing the steam and exhaust valve operated in accordance with my invention. Figs. 2 and 3 are sectional views, respectively, of the steam-valves; and Fig. 4 a side elevation showing the preferred manner of operating the steam-valves.

A is the steam-cylinder; B, the steam-valves; C, the exhaust-valves.

D represents a revolving shaft carrying at one end a miter-gear D', through which it is revolved by the driving-shaft E, and at its opposite end a miter-gear F, meshing with a miter-gear carrying on the same shaft a spur-gear G, which latter meshes with spur-gears of the same size G' G², located, respectively, above and below the spur-wheel G. The spur-wheel G² carries a wrist-plate H' to an eccentric-pin, upon which are connected the rods I and I', which at their opposite ends are connected with the exhaust-valve-operating levers I² I³. It may be stated, however, that this means of operating the exhaust-valves is capable of such variation as may be deemed desirable, as it does not present an essential feature of my construction. The wrist-plate H, carried by the spur-wheel G', carries an eccentric-pin K, to which are connected rods L L'.

Mounted at a convenient location, preferably over the shaft D, is a small steam-cylinder and piston M, of common construction, the piston of which is steam-cushioned and the steam-valve of which is operated by a rod M', connected with the eccentric M², controlled by the governor N. This governor is preferably constructed in accordance with Letters Patent No. 249,630, granted to me November 15, 1881, and is readily adjustable through the medium of the lever N'. The piston in the cylinder M carries a jointed connecting-rod O, which extends from the cylinder across the steam-cylinder A at a point opposite the steam-valves therein. To the valve-stem of each steam-valve B is connected a short crank P. The opposite end of this crank is pivotally connected, as at P', to the link R, one end of which is pivotally connected to the rod O and the other end of which is pivotally connected to the rods L L', respectively.

60 The operation of my invention is as follows: Under the action of the eccentric M², admitting steam behind the piston in the cylinder M, the rod O is shifted across the valve B, carrying with it the upper end of the link R and moving the cranks P to close the valve. By reason of the connection of the link R at its lower end to the wrist-plate H, which lat-

ter is revolved by the shaft D, an obstacle is presented to the opening of the other valve under the sudden and instantaneous action 70 of the rod O, and the operation of opening is effected by the movement of the lower end of the link R as the wrist-plate H revolves and directly actuates it.

In Fig. 1 I have illustrated in full and dotted lines, respectively, the positions of the links R under the operation of the cylinder and piston M when the piston is at half-stroke. It will be understood, however, that when the upper end of the links R reaches the point S 80 the lower end of the links may be at any intermediate point, being restrained by the retarded position of the rods L L' through their connection with the wrist-plate. Steam may thus be admitted during the whole piston-stroke, or nearly so; but when the steam-pressure of the auxiliary piston is reversed during any part of the piston-stroke then the upper end of the links will at once be shifted the full stroke and will close the valve instantly 90 for the remaining part of the stroke. The valve motion of the auxiliary cylinder is controlled by a governor, which changes the lead of eccentric M², Fig. 4.

To extend the range of cut-off the whole length of the piston-stroke, it is necessary to shift the eccentric one hundred and eighty degrees on the shaft, which is accomplished by the normal governor described in my Letters Patent No. 249,630, dated November 15, 1881. 100 The governor-shaft is driven in unison with the engine-shaft by a belt-link. The governor-balls are held together by a spring, and when the centrifugal force of the balls overbalances the tension of the spring then the 105 eccentric M², Fig. 4, is driven forward by a train of differential gears. The tension of the governor-spring is for the present purpose regulated by a counter-spring on lever N, Fig. 4. By giving more or less tension to this 110 counter-spring, which can be done while the engine is running, the speed of the engine is varied without interfering with the automatic regulation of the expansion. The governor-shaft revolves in the same direction always, 115 whether the engine runs forward or back. This is effected by a self-acting clutch on the governor-shaft, which at the same time reverses the lead of the eccentric M² when the engine is reversed. In this manner the 120 automatic regulation of the expansion for any reasonable resistance within the power of the engine will be maintained at any desired speed. Manipulation of the engine is thereby made less laborious, the engineer controlling the speed by a light lever or hand-wheel, the economical regulation being always automatic and out of his control. It will be understood that the auxiliary piston always moves to close the port at one end of the cylinder when or before the engine-piston arrives at the other end. Therefore at the beginning of each stroke the upper end of the links is held by the auxiliary piston firmly at

the right place for the positive opening of the port, so that the lead of the valve remains constant. By regulating in this way throttling is avoided under any speed, thus maintaining the advantage of expansion.

5 The reversing of the engine is best done in some manner which excludes a permanent checking of the speed, so as to take the regulation of the expansion out of the engineer's hands. I have shown my device associated with a rotary valve; but it will be understood that the principle of its operation may easily be applied in connection with any other form of valve which may be adopted. While with 10 the Corliss gear a slow toggle motion is useful at the beginning of the valve-stroke to secure promptness in hooking on and the quick back-stroke is therein unobjectionable because the motion-rod is kept up by air-pressure. 15 To the same side of the wrist, for a quick positive action this is different and the uniform rotary motion is preferable.

The cost of making the valve-gear herein described and claimed is moderate when compared with others for a similar purpose. It 20 requires less attention from the engineer. It is suitable for high speed, while reduced speed does not interfere with the expansion best adapted to the resistance. As before stated, 25 the valve-gear consumes less power than any automatic cut-off where a vacuum must be maintained for closing the valves. For the same reason it takes less power to reverse the valves.

What I claim as new, and desire to secure 35 by Letters Patent, is—

1. In combination with the steam-valves of a steam-engine, a valve-operating rod driven by a power regulated directly by the governor, and a valve-operating rod driven through the 40 main driving-shaft, and a jointed connection between said rods at each valve, substantially as described.

2. In combination with the steam-valves of a steam-engine, a crank on said valves, links 45 connected at their centers, respectively, to each crank, operating-rods connected, respectively, to the upper and to the lower ends of the links, and a connection between one of said rods and the main driving-shaft, and an 50 auxiliary driver for the other rod, substantially as described.

3. The combination, with the steam-valves B and their operating-cranks P, of the links R, wrist-plate H, driven from the driving-shaft, connecting-rods L L', joining the links R at their lower ends to eccentric wrist-pins on the plate H, rod O, connected to the upper end of the links R, piston and cylinder M, actuating said rod, and governor N, having 55 an eccentric connection with the steam-valves of the steam-cylinder M, said parts being arranged to operate substantially as set forth.

MAXIMILIAN JACKER.
